ASH TRAY

Howard A. Packard, Albany, N. Y.

Application June 2, 1950, Serial No. 10,320

Term of patent 14 years

(Cl. D85—2)

To all whom it may concern:

Be it known that I, Howard A. Packard, a citizen of the United States, residing at Albany, in the county of Albany and State of New York, have invented a new, original, and ornamental Design for an Ash Tray, of which the following is a specification, reference being had to the accompanying drawing, forming part thereof.

Fig. 1 is a top plan view of an ash tray showing my new design;

Fig. 2 is a side elevational view; and

Fig. 3 is an end elevational view thereof.

I claim:

The ornamental design for an ash tray, substantially as shown.

HOWARD A. PACKARD.
